U.S. Cl. D90—20

FIG. 1

FIG. 2

FIGURE 1 is a view in side elevation of a tire showing my new design, the side opposite that shown being substantially a mirror image;

FIGURE 2 is an enlarged view in side elevation thereof rotated 90° with respect to FIGURE 1, the tread design shown being substantially identical throughout the circumference of the tire; and

FIGURE 3 is an enlarged view thereof in transverse section as seen from the line 3—3 of FIGURE 1.

I claim:

The ornamental design for a tire, substantially as shown and described.
